UNITED STATES PATENT OFFICE.

LOREN CRAMER, OF GALVA, KANSAS.

DESIGN FOR A WRENCH BOXING MEMBER.

SPECIFICATION forming part of Design No. 30,197, dated February 14, 1899.

Application filed January 19, 1899. Serial No. 702,723. Term of patent 14 years.

To all whom it may concern:

Be it known that I, LOREN CRAMER, a citizen of the United States, residing at Galva, in the county of McPherson and State of 5 Kansas, have invented and produced a new and original Design for a Wrench Boxing Member, of which the following is a specification.

This invention relates to a new and original 10 design for a wrench boxing member; and it has for its object to provide a design of this character that shall be both useful and ornamental.

The leading feature of the design resides 15 in a flat body-plate provided at opposite side edges with parallel semicylindrical sleeve portions, one of which is coextensive with the length of the plate and the other of which is of a greater length than the plate and extended beyond one end thereof.

While the essential feature of the design resides in the flat plate provided at its longitudinal side edges with parallel semicylindrical sleeve portions of different lengths, the 25 invention also embodies several minor features, which are the flat body-plate, being of a rectangular shape and provided therein with a pair of spaced openings, and the semicylindrical sleeve portions provided at their edges 30 with offstanding approximately U-shaped perforated ears.

In the drawings, Figure 1 is a perspective

view of a wrench boxing member embodying the herein-described design. Fig. 2 is a plan view thereof. Fig. 3 is a cross-sectional view 35 on the line 3 3 of Fig. 2.

Referring to the accompanying drawings, the numeral 1 designates the body-plate of the boxing member. This body-plate is of a rectangular shape and provided therein with 40 a pair of spaced openings 2. The said rectangular flat body-plate 1 is also provided at the opposite longitudinal side edges thereof with the integral concavo-convex semicylindrical sleeve portions 3 and 4, respectively, 45 the sleeve portion 3 being coextensive with or of the same length as the body-plate 1 and the sleeve portion 4 being of a greater length than the body-plate and having an extension 50 projecting beyond one end of the plate. 50

To complete the design, the opposite parallel semicylindrical sleeve portions 3 and 4 are provided at their edges with offstanding approximately U-shaped perforated ears 6.

What is claimed is—

The design for a wrench boxing member, herein shown and described.

In testimony that I claim the foregoing as my own I have hereto affixed my signature in the presence of two witnesses.

LOREN CRAMER.
